(57) **CLAIM**

We claim the ornamental design for a ceiling ventilating fan, as shown and described.

DESCRIPTION

FIG. 1 is a front perspective view of a ceiling ventilating fan of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a cross-section view taken along the line 8—8 of FIG. 2.

The broken line showing of ceiling ventilating fan is included for the purpose of illustrating environment and forms no part of the claimed design.
